ALARM MECHANISM

Stanley W. Stout, Flint, Mich., assignor of one-fourth to Josie McKay Gordon, Flint, Mich.

Application October 8, 1932. Serial No. 636,801

8 Claims. (Cl. 116—94)

The present invention relates to an improvement in alarm mechanisms of the type employed to detect movement of any object; the object usually being a window or door of a dwelling or the like.

It is the primary object of this invention to provide a control mechanism for an alarm which is operated by a cord or the like secured to the object, upon movement of which detection is desired, capable of sounding an alarm upon cutting or movement of the cord in either direction.

Another object of this invention is to provide an alarm in the form of a bell or gong which will not be mistaken for the usual alarm of the telephone, door bell or alarm clock.

These and other objects and advantages will appear as the description proceeds. It is to be clearly understood, however, that I do not desire to be restricted to the exact details shown and described, but intend to include as part of my invention, all such changes and modifications which would occur to those skilled in the art and fall within the scope of the appended claims.

In the drawing wherein a preferred embodiment of my invention is shown,

Fig. 1 is a plan view of the gong operating and control mechanism taken on line 1—1 of Fig. 2 with the bearing plate 4 removed.

Fig. 2 is a side elevational view of the gong operating and control mechanism; the cover being shown removed along the longitudinal center line.

Fig. 3 is a detailed view of the control mechanism.

Fig. 4 is a bottom view of the bell gong detached from its mounting.

Fig. 5 is a detailed view of the hammer.

Fig. 6 is a detailed view of the bracket employed to retain the spring case in position.

With reference to the drawing, in Figs. 1 and 2 is shown a base member 1 of sufficient weight to offer considerable resistance to movement in a horizontal direction. An inverted disk shape cover portion 2 is removably secured to the base 1 by screws 3 or the like. A bearing plate 4 is fixedly spaced from the upper face of the base 1 by posts 5 threadedly secured in the base 1. A shaft 6, having a square end 7 to receive a winding key inserted through the opening 8 of the

cover 2, has journaled portions 9—10 guided for rotation in the plate 4 and base 1, respectively. The usual spring motor (not shown) has one end attached to the shaft 6 and the other end attached to the inside of the spring case 11 suspended from the plate 4 and prevented from rotating by the

brackets 12. The large main gear 13 is loosely mounted on the shaft 6 and adapted to be driven in one direction by pawl and ratchet connection (not shown) with the spring driven shaft 6. The gear 13 may be spaced from the base 1 by a washer 14 or the like.

The gear 13 meshes with a pinion 15 on a shaft 15 which in turn carries a gear 16. Likewise, the gear 16 meshes with a pinion 17 on the shaft 18 and drives a gear 19 meshing with a pinion 20 fixedly secured to the hollow shaft 21. The shaft 21 is journaled upon a post 22 threadedly secured in the base 1 and adapted to support a bell or gong 23 screwed to the upper end.

A hammer member 24 preferably formed from a helical coil, with a solid tip 25, is anchored to a collar member 26 which is clamped to the hollow shaft 21. The gong or bell 23 is provided with a plurality of fins 27 with which the hammer 24 is adapted to contact upon rotation.

A circular plate 28 is fixedly secured to the lower end of the shaft 21 and is adapted to rotate therewith. One or more stop lugs 29 are provided upon the periphery and project into the path of a slideable pin to control the sounding of the alarm as will be hereinafter described.

The alarm control mechanism consists of a bearing block 30 secured to the base 1 by any suitable means. The block 30 has an overhanging shoulder 31 which acts as a bearing for the operating member 32 having a horizontal portion 33. A cam 34 is affixed to the lower end of member 32 and has a flat face portion 35 which abuts a sliding cam follower 36 secured to a pin 37 supported in the block 30 for longitudinal movement. As shown in Fig. 1 the outer end of the pin 37 is in the path of the lugs 29 and prevents the rotation of the shaft 21 to sound the alarm. In order to lock the pin 37 in the position shown, a vertical shaft 38 is rotatably journaled in the base 1 and the cover 2. A cam 39 is affixed to the lower end of the shaft 38 and contacts with the follower 36 to lock the pin 37 in the outward position as shown in Fig. 1. A handle 40 of any suitable construction is provided at the upper end of the shaft 38 to selectively position the cam 39.

A spring 40 is secured at one end to a post 41 and at the other end to the arm 33. As shown in Fig. 1, the spring 40 is under tension tending to rotate the shaft 32 and cam 34 but is prevented from doing so by the locking cam 39. A cord 42 or the like is also secured to the other end of the arm 33 and is adapted to be secured to

some object, the movement of which is to be detected.

The operation of the above described mechanism is as follows: With the locking cam 39 in the position shown in Fig. 1, energy is stored up in the spring mechanism in the usual manner. The cord 42 is then secured to the object, the movement of which is to be detected, for example, a door, window, etc., and the entire alarm mechanism is moved longitudinally of the cord upon a supporting surface for the base 1 until the cord is taut. The handle 40 is then rotated to remove the cam 39 from the follower 36. Under this condition, the tensioned spring 40 is tending to rotate the arm 33 and cam 34 but is prevented from doing so by the resistance of the cord 42; the weight of the base 1 and supported mechanism being sufficient to overcome sliding of the same upon the supporting surface under the stress of the spring 40 upon the post 41. With the alarm mechanism in a set condition any movement of the cord in either direction or the cutting of the cord will result in the rotation of the shaft 32 and cam 34 in one direction or the other. Thus it will be apparent that the cam 34, in contact with the follower 36, will move the follower 36 in the direction of the cam 39 to remove the pin 37 from the path of the lug 29. With the plate 28 free to rotate, the shaft 21 and hammer 24 will be rotated at a high speed to sound a high pitch alarm unmistakably distinguishable from the usual telephone and clock alarm.

Obviously, any other well known source of energy may be employed to rotate the shaft carrying the hammer 24. For example, I anticipate the employment of my alarm control mechanism in combination with an alarm clock. Likewise, the movement of the pin 37 could be employed to make or break an electric circuit when the gong hammer is electrically driven. Regardless of the type of hammer operating mechanism, my invention primarily resides in a compact portable alarm mechanism having an alarm control which will sound an alarm upon release or movement in either direction of the member transmitting the movement of the object being detected.

Having described my invention what I claim as new and desire to protect by Letters Patent is:

1. In an alarm of the type to be sounded upon movement of an object, the combination with a gong, of a motor driven hammer for said gong, means rendering the alarm inoperative in one position, a control member operatively associated with said means, means urging said member in one direction to render the alarm operative, a cord secured to said member to move the same in the other direction to render the alarm operative and adapted to be connected to the object, said cord under determined tautness positioning said control with said first means in the position rendering said alarm inoperative, and means associated with said first means locking said alarm in an inoperative position against being rendered operative by said member by movement in either direction.

2. In an alarm of the type to be sounded upon movement of an object, the combination with a gong, of a motor driven hammer for said gong, means rendering the alarm inoperative in one position including a cam follower, a control member having a cam, means urging said member in one direction, a cord secured to said member to move the same in the other direction and

adapted to be connected to the object, said cord under determined tautness positioning said cam in an intermediate position, said cam being adapted to contact with said follower upon movement in either direction from said intermediate position to render the alarm operative.

3. In an alarm of the type to be sounded upon movement of an object, the combination with a gong, of a motor driven hammer for said gong, a pin for locking the hammer operating mechanism in an inoperative position a cam follower secured to said pin, a control member having a cam, a spring urging said member in one direction, a cord secured to said member to move the same in the other direction and adapted to be connected to the object, said cord under determined tautness positioning said cam in an intermediate position, said cam being adapted to contact with said follower upon movement in either direction from said intermediate position to render the alarm operative.

4. In an alarm of the type to be sounded upon movement of an object, the combination with a gong, of a motor driven hammer for said gong, a member movable with said hammer, a pin supported for longitudinal movement, coacting with said member in one position to render the alarm inoperative a cam follower secured to said pin, a control member having a cam, a spring urging said member in one direction, a cord secured to said member to move the same in the other direction and adapted to be connected to the object, said cord under determined tautness positioning said cam in an intermediate position, said cam being adapted to contact with said follower upon movement in either direction from said intermediate position to render the alarm operative.

5. In an alarm of the type to be sounded upon movement of an object, the combination with a gong, of a motor driven hammer supported upon a vertical shaft, a lug supported on said shaft, a pin supported for longitudinal movement coacting with said member in one position to render the alarm inoperative, a cam follower secured to said pin, a control member having a cam, a spring urging said member in one direction, a cord secured to said member to move the same in the other direction and adapted to be connected to the object, said cord under determined tautness positioning said cam in an intermediate position, said cam being adapted to contact with said follower upon movement in either direction from said intermediate position to render the alarm operative.

6. In an alarm of the type to be sounded upon movement of an object, the combination with a gong, of a motor driven hammer for said gong, means rendering the alarm inoperative in one position including a cam follower, a control member having a cam, a spring urging said member in one direction, a cord secured to said member to move the same in the other direction and adapted to be connected to the object, said cord under determined tautness positioning said cam in an intermediate position, said cam being adapted to contact with said follower upon movement in either direction from said intermediate position to render the alarm operative, and a selectively operated cam adapted to contact with said follower to prevent movement of the same to render the alarm operative.

7. In an alarm of the type described, the combination with a gong, of means for sounding said gong, means capable of rendering the alarm in-

operative in one position, a control member having operative connections with said second means and capable of movement in opposite directions, said connections between said member and means being effective upon movement of said member in either direction to move said second means to an ineffective position to sound the alarm, and means independent of said control member solely capable of rendering said second means again effective.

10 8. In an alarm of the type described, the com-

bination with a gong, of means for sounding said gong, means capable of rendering the alarm inoperative in one position, a control member having operative connections with said second means and capable of movement in opposite directions, 80 said member only upon initial movement in either direction moving said second means to an ineffective position to sound the alarm, and means independent of said member solely capable of rendering said second means again effective. 85
